UNITED STATES PATENT OFFICE.

ERNEST KRAUS, OF LYNN, MASSACHUSETTS, ASSIGNOR TO GENERAL ELECTRIC COMPANY, A CORPORATION OF NEW YORK.

ELECTRICAL CUT-OUT.

1,189,973.

Specification of Letters Patent.

Patented July 4, 1916.

Application filed November 28, 1914. Serial No. 874,422.

To all whom it may concern:

Be it known that I, ERNEST KRAUS, a citizen of the United States, and residing at Lynn, in the county of Essex, State of Massachusetts, have invented certain new and useful Improvements in Electrical Cut-Outs, of which the following is a specification.

The present invention relates to the construction of devices which are selectively responsive to electrical currents at different voltages and which contain a material, such, for example, as boron, having a high negative temperature coefficient of resistance, the initial high resistance breaking down when the impressed voltage exceeds a certain value.

Boron is very hard and brittle and hence difficult to shape mechanically. The electrical characteristics of boron are such that when it is to be used in electric devices at commercial voltages thin films must be employed. For these reasons it has been found very difficult to mechanically shape a boron conductor which will have certain predetermined electrical characteristics and will regularly maintain these characteristics in service.

It is the object of my invention to provide an electrical cut-out device which will have a sharp break-down voltage which may be adjusted independently of the current-carrying capacity and which will regularly continue to break down at the same voltage even after continued service. A cut-out of this description may be used to automatically complete a circuit in shunt to a device, such, as for example, a lamp, in a series circuit when the voltage across the terminals of the device rises unduly, or when the device fails entirely.

In accordance with my invention a coiled filamentary conductor consisting largely of boron is prepared by chemically depositing boron on a relatively fine filament of conductive material, such, for example, as carbon or tungsten, and electrical contact is made on the inside and outside of this coiled filament so as to secure a unitary structure which is mechanically rugged and can be inserted in a circuit in standard contacts.

The accompanying drawing shows in section somewhat enlarged a form of electrical cut-out embodying my invention.

In order to illustrate my invention I will

describe the structural features with respect to the specific example, but of course it should be understood that my invention is not limited to the specific details described. I may start with a helical filament of carbon about two and one-half mils in diameter, the helix being about one-fourth inch in length and the turns about one-thirty-second inch apart. The diameter of the helix across the turns may be about three-thirty-seconds of an inch. This filament is connected to a suitable current-conveying terminal and is then rendered incandescent in a mixture of boric chlorid and hydrogen. This treatment may be carried out in a mixture of about ten parts boric chlorid and seven parts hydrogen, the duration of treatment depending upon the properties desired in the finished cut-out. In some cases, a gaseous compound of carbon, such as gasoline or benzol, may be added to the mixture thereby adding carbon to the boron and lowering its resistance. As the carbon core may be made relatively fine, there is little tendency for subsequent change in the electrical properties of the boron by chemical combination with the core. The helical conductor 1 thus obtained consisting of a core of carbon and a coating of boron is then placed upon a rod 2 of conductive material, for example, copper or other metal, the diameter of the rod being so chosen that a firm contact is secured. As the boron deposited on the helix is very hard the helix may be manipulated to cut itself threadlike into the metal rod. A contact is secured upon the outside of the boron by dipping it in molten metal, for example, lead, or in any other desired manner, securing a mass of conductive material 3 on the outside of the boron which will not only serve as an electrical conductor but will also rigidly secure the respective parts to form a single structure. I have found that even when the turns of the spiral are out of contact with each other that the molten metal will not come into contact with the inner core providing the spaces between the turns are not too great. For convenience of inserting such a cut-out into standard clamps or contact devices similar to those employed for fuses, the molten metal is preferably contained in a metallic cup 4. Contact with the rod 2 at the ends of the helical conductor is prevented by an insulating cement 5. A similar metallic cup 6 also filled with

metal is preferably attached to the opposite end of the conductive rod 2 so as to make the structure symmetrical.

One of the main advantages of the above described form of cut-out lies in the possibility of varying the current-carrying capacity without disturbing the structural relations of the core and shell of the boron helix. An increase in current-carrying capacity may be secured by properly choosing the dimensions of the helix and the metal parts contacting therewith, but the core upon which the boron layer is deposited need be no greater than in a cut-out of less capacity. As the core is small in all cases, the voltage at which the resistance of the boron breaks down may not only be accurately predetermined but is not likely to change by absorption of conductive material from the core. Although I have described the construction of the cut-out with particular reference to boron, I wish it to be understood that my invention is also applicable to other material, for example, silicon, having a high coefficient of resistance.

What I claim as new and desire to secure by Letters Patent of the United States, is:—

1. An electrical cut-out comprising, a helix consisting largely of boron, a rod of conductive material making electrical con-

tact with the inner surface of said helix and means for electrically contacting with the outer surface of said helix.

2. An electrical cut-out, comprising a body of conductive material, a filamentary body consisting largely of boron coiled about said body, and a mass of conductive material surrounding and rigidly binding said boron body but out of electrical contact with said core. 40

3. As an article of manufacture, a helical conductor having a coating of boron, a rod of conductive material contacting with the inner surface of said helix, and a mass of metal surrounding the outer surface of said 45 helix.

4. An electrical cut-out comprising a filament having a relatively fine core of conductive material and a deposit of boron thereon, electrical terminals extending lengthwise 50 said filament on opposite sides of the outer surface of said boron deposit, and means for maintaining said terminals spaced and out of contact with each other.

In witness whereof, I have hereunto set 55 my hand this 25th day of November, 1914.

ERNEST KRAUS.
